P. F. VAN PATTEN

GOLFING TEE

Filed May 7, 1928

INVENTOR.

Paul F. Van Patten.

BY *Thomas J. Kennedy*
ATTORNEY.

UNITED STATES PATENT OFFICE.

PAUL F. VAN PATTEN, OF DETROIT, MICHIGAN, ASSIGNOR TO STERLING H. CAMPBELL, OF ST. LOUIS, MISSOURI.

GOLFING TEE.

Application filed May 7, 1928. Serial No. 275,887.

My invention relates to a new and useful improvement in a golfing tee, and has for its object the provision of a tee which will be simple in structure, economical of manufacture, and highly efficient in use.

Another object of the invention is the provision of a tee which, when used and properly aligned, will present to the driving club a surface extended parallel to the face of the driving club, when in proper position.

Another object of the invention is the provision of a golfing tee having a plurality of tees of various heights mounted thereon, so arranged and positioned that when one is being used an open space between the other tees is provided for the passage of the club.

Another object of the invention is the provision of a tee formed from a plate having a carrying opening formed therein.

Other objects will appear hereinafter.

The invention consists in the combination and arrangement of parts hereinafter described and claimed.

The invention will be best understood by a reference to the accompanying drawings which form a part of this specification, and in which,

Fig. 1 is a top plan view of the invention.

Fig. 2 is a side elevational view of the invention.

Fig. 3 is a sectional view taken on line 3—3 of Fig. 1.

As shown in the drawings the invention comprises a plate 7 formed preferably from hard rubber or the like and formed triangular shaped. This plate is provided with an opening 8 through which the handle of the golfing club may be projected for carrying the tee from place to place.

At one corner of the plate 7 there is provided an elevation 9 with an opening 10 formed therein, this elevation serving as a tee and the opening serving as a retainer or support for the golf ball placed thereon.

Formed on one of the other corners of the plate 7 is a projection 11 having a pocket 12 formed therein, this projection 11 being of greater height than the projection 9.

Formed on the other corner is a projection 13 of greater height than either of the projections and provided with a pocket 14 for the reception of the ball.

In use, when either of the tees is being used,

the side of the triangle opposite the tee is placed in position next to the user with the face at right angles to the line determined by the player, the tee 11 and the position to which the drive is to be made, so that the face of the plate directed toward the driver will determine a surface at which the driver may align the driving face of the club. As the drive is made, it will be noted that there will be sufficient space between the other two tees on the plate to permit the passage of the club therethrough, so that a plurality of tees are used on the face and when in use the player is not interfered with by the presence of any of the tees which are not being used.

While I have illustrated and described the preferred form of my invention, I do not wish to limit myself to the precise details of structure shown, but desire to avail myself of such variations and modifications as come within the scope of the appended claims.

Having thus described my invention what I claim as new and desire to secure by Letters Patent is:

1. A golfing tee of the class described, comprising: a triangular shaped plate; and a plurality of tees projecting outwardly from one face thereof, each at one corner of said plate.

2. A golfing tee of the class described, comprising: a triangular shaped plate; and a plurality of tees projecting outwardly from one face thereof, each at one corner of said plate, each of said tees being of a height differing from the other tees.

3. A golfing tee of the class described, comprising: a triangular shaped plate; and a plurality of tees projecting outwardly from one face thereof, each at one corner of said plate, each of said tees being of a height differing from the other tees, said plate having an opening centrally therein.

4. In a device of the class described, the combination with a base, of three tees carried on said base and forming the apices of a substantially equilateral triangle.

5. In a device of the class described, the combination with a base, of three tees carried on said base and forming the apices of a substantially equilateral triangle, said tees varying in height.

In testimony whereof I have signed the foregoing specification.

PAUL F. VAN PATTEN.
